UNITED STATES PATENT OFFICE.

GUSTAVE E. VILLARET, OF LEONIA, NEW JERSEY, ASSIGNOR TO HARRY HILFMAN,
OF NEW YORK, N. Y.

DESIGN FOR A SCROLL ARM FOR LIGHTING FIXTURES OR SIMILAR ARTICLES.

Application filed March 1, 1926. Serial No. 16,718. Term of patent 3½ years.

To all whom it may concern:

Be it known that I, GUSTAVE E. VILLARET, a citizen of the United States, residing in the city of Leonia, county of Bergen, and State of New Jersey, have invented a new, original, and ornamental Design for a Scroll Arm for Lighting Fixtures or Similar Articles as shown, of which the following is a specification, reference being had to the accompanying drawing, forming part thereof.

In the drawing, Figure 1 is a plan view of a scroll arm for lighting fixtures.

Figure 2 is a side view of the same.

I claim:

The ornamental design for a scroll arm for lighting fixtures or similar articles as shown,

GUSTAVE E. VILLARET.
